APPARATUS FOR LOADING TRUCK
TRAILERS ON SHIPS

Henry D. Cleveland, New York, N. Y.

Application December 27, 1949, Serial No. 135,232

2 Claims. (Cl. 214—15)

1

This invention relates to ship construction and method and apparatus for loading and supporting truck trailers on ships, for storing them thereon and for thereafter unloading them therefrom, thereby linking the highway and the waterway.

The present invention constitutes an improvement over the invention shown and described in applicant's co-pending application, Serial No. 19,215, filed April 6, 1948, now abandoned. The co-pending application describes a method of loading and unloading trailers across the sides of the ship. Movable gangways are therein provided for this purpose, and the trailers are stored on the ship's decks, athwartship, and rest upon their own wheels. It has been found that movable gangways, while practicable and practical, do possess certain disadvantages which are not inherent in conventional gangways, and it is accordingly a principal object of this invention to provide loading and unloading apparatus of the character described wherein conventional gangways are utilized for loading and unloading the truck trailers. These conventional gangways are permanent features of the wharves or piers where they may be used to load and unload both sides of the ship simultaneously as well as two or more decks simultaneously.

Another disadvantage of the apparatus disclosed in said co-pending application resides in the fact that it relates solely to loading and unloading the ship but it does not provide facilities for properly storing the truck trailers on board ship and securing them against the pitch and roll at sea. It is, therefore, another principal object of this invention to provide apparatus for properly storing the truck trailers on board ship, said apparatus including means for elevating the truck trailers so that the load is removed from their wheels and for supporting the trailer chassis directly by supporting means carried by the ship.

In the form of the invention shown in the co-pending application, movable gangways are provided so that the truck trailers may be loaded on board ship at selected locations. In the present form of invention, one or more conveyor systems are provided on each deck of the ship, and these conveyor systems perform the function of properly stowing the truck trailers on board ship. It is, therefore, still another important object of the invention to provide apparatus on board ship for handling the truck trailers thereon, and moving them from one location to another.

The advantages of the present invention are manifold. In the first place, the apparatus here-

2

in described and claimed renders it possible to load and unload trailers at a faster rate of speed than is possible with any other kind of apparatus. In the second place, the cost of constructing and maintaining conventional gangways as distinguished from travelling gangways, is exceedingly low. In the third place, a constant draft is maintained both at sea and in port, except when the ship is out of service and this, of course, simplifies and facilitates the operation. In the fourth place, the present apparatus requires that one truck trailer be unloaded before another can be loaded to take its place and hence, the ship will always be maintained at an even keel. A fifth advantage is inherent in the fact that the truck trailers are anchored quickly and firmly to the ship as soon as they are loaded thereon, and placed in their proper locations, without the use of lift jacks or other similar apparatus and also without the use of turnbuckles or the like for fastening them to the ship's decks. They rest of their own weight on supports which engage their chassis and there is no need for further anchoring them to the ship. A sixth advantage resides in the fact that the truck trailers cannot rock relative to the deck of the ship as would normally be the case when they rest upon their own wheels and springs. This prevents damage both to the ship and to the trailers, and it also avoids the dangers of a shiftable or otherwise movable cargo. It is also advantageous to the tires and springs of the truck trailers themselves, to remove all concentrated loads therefrom for the period of time it would take the ship to sail from one port to another. A seventh advantage resides in the fact that the truck-supporting apparatus of the present invention avoids the concentrated loads which the decks would otherwise be required to bear, thereby making for a reduction in the weight of the deck plating and of the structural supports on which the deck plating rests. The trailer-truck supporting members may be so designed as to serve as reinforcing members in the ship construction. There are other advantages which are inherent in the present invention.

A principal object of the present invention is the provision of improved and unique trailer supporting means and apparatus for supporting the trailers on the decks of the ship. Specifically, this includes an elevated conveyor belt which supports the back end of the trailers, a second conveyor belt which is disposed at a relatively low level for supporting the front end of the trailers, and a temporary, portable fifth wheel assembly which is interposed between the front end of

each trailer and the second mentioned conveyor belt so that actually the front end of the trailer rests upon the fifth wheel assembly and said assembly rests upon the second mentioned conveyor belt. A ramp is provided for the rear wheels of the trailer so that the back end of the trailer may be raised to the level of the first mentioned conveyor belt. The ramp may be raised or lowered as and when desired. A tractor with a hydraulic lift adapted to engage the fifth wheel assembly is provided to support the fifth wheel assembly during the loading and unloading operations and it is by this means that said fifth wheel assembly may be raised or lowered as and when desired. In other words, the fifth wheel assembly performs two functions: it is the means whereby the tractor may be coupled to the trailer for loading and unloading purposes, and it is also the means which supports the front end of the trailer on the second mentioned conveyor belt during the course of the ship's voyage from the port of loading to the port of unloading.

A preferred form of the present invention is shown by way of illustration in the accompanying drawing, in which:

Fig. 1 is a side view of a trailer carrying ship made in accordance with the present invention.

Fig. 2 is a cross-sectional view through said ship and it is also a view of some of the shore facilities for loading and unloading the ship.

Fig. 3 is a top view of three such ships, showing one of them in a slip, the shore facilities for loading and unloading the trailers being shown on both sides of the slip.

Fig. 4 is an exploded view of the three elements, in addition to the ship itself, which the present invention involves: the trailer, a portable fifth wheel assembly for said trailer, and a tractor which utilizes said portable fifth wheel assembly in moving the trailer from ship to shore and from shore to ship.

Fig. 5 is an exploded top view of said tractor and said fifth wheel assembly.

Fig. 6 is a side view thereof.

Fig. 7 is a fragmentary side view showing the fifth wheel assembly supported by the tractor and the trailer supported by the fifth wheel assembly.

Fig. 8 is a fragmentary transverse section through one of the ships showing how the trailers are loaded thereon and unloaded therefrom.

Fig. 9 is a fragmentary top view of one of the decks of the ship showing two of the conveyor belts which are used to support the trailers and to move them from one position to another on the ship.

Fig. 10 is an enlarged cross-sectional view showing the details of one of the conveyor systems, that is the conveyor system which supports the front end of the trailers.

Fig. 11 is a view looking in the direction of arrows 11, 11 of Fig. 10.

Fig. 12 is a view similar to that of Fig. 10, showing the conveyor system which supports the back end of the trailers.

Fig. 13 is a view looking in the direction of arrows 13, 13 of Fig. 12.

Fig. 14 is a fragmentary top view of one of the ramps on which the rear wheels of the trailer ride up upon and down from the rear conveyor belt.

Fig. 15 is a side view thereof.

Fig. 16 is a diagrammatic view showing the drive mechanisms for the two conveyor belt systems.

Fig. 17 is a view similar to that of Fig. 3, but

showing different shore facilities for loading and unloading the ship.

The principle of operation of the present invention is as follows: Truck trailers are loaded upon the ship at a given port, they are carried by the ship to a second port, and they are unloaded. Conventional tractors are employed to deliver the trailers to the wharves at the first port and conventional tractors are also utilized to remove the trailers from the wharves at the second port. Special tractors, herein described, and special apparatus, also herein described, are utilized for the purpose of loading the trailers upon the ship and unloading them from the ship. Apparatus is provided on board ship for supporting the trailers, not on their wheels or springs, but rather on their chassis during the course of the voyage between the two ports and the same apparatus, also is employed to move the trailers from place to place on board ship. Said apparatus is also described herein. The facilities for loading and unloading the ship are independent of each other in the sense that the ship may be loaded and unloaded at the same time. More specifically, while one trailer is taken off the ship, another trailer may be brought aboard ship. An important feature of the present invention, as will more fully hereafter appear, is the supporting member which supports the front end of the trailer both on board ship and while it is being moved either onto or off the ship by means of the tractor.

It will be seen in Figs. 1, 2, and 3, that a ship 20, designed in accordance with the present invention, is provided with two decks 21 and 22, respectively, on which trailers 23 may be loaded. Each deck may be considered as being divided into two longitudinal sections, one on the port side of the ship and the other on its starboard side. Doors 25 are provided on both sides of the ship so that both longitudinal sections may be rendered accessible simultaneously both for loading and unloading purposes. Each longitudinal section is further divided or partitioned by means of transverse bulkheads 26 into relatively small sections or compartments, each of which is adapted to accommodate a given number of trailers, say eight. (See Figs. 3 and 9.)

Since the ship is divided into port side compartments and into starboard side compartments, and since it is provided with doors to said compartments on both sides thereof, it may be loaded and unloaded simultaneously across both sides as Fig. 2 clearly shows.

It will be seen that ship 20 may be brought into a slip 27 with banks or wharves 28 and 29 on both sides thereof. Some of the trailers may be brought onto the lower deck 22 directly from the wharves and across gangplanks 30. Ramps 31 and 32 are needed, however, in order to load trailers upon the upper deck 21. Gangplanks 33 may be employed to bridge the gaps between upper deck 21 and ramps 31 and 32, respectively. It will be noted that ramps 31 and 32 parallel the surface of the wharves for a considerable distance on both sides of the ship and they descend to the wharves well beyond the sides of the ship. The parallel sections of ramps 31 and 32 are raised well above the level of wharves 28 and 29 so that trailer trucks may be moved freely beneath said parallel sections of the ramps.

Reference to Fig. 3 will disclose the fact that since the ship under discussion is provided with ten trailer compartments on each deck, that is five on each side thereof, it may be found desirable to provide six ramps on each side of the

boat, to wit, ramps 31a, 31b, 31c, 31d, 31e, and 31f, on one side, and ramps 32a, 32b, 32c, 32d, 32e, and 32f, on the other side. It will be noted that ramps 31b, 31c, 31d, 31e, 32b, 32c, 32d, and 32e are double lane ramps, that is they are each sufficiently wide to accommodate two trailers side by side. These double ramps are used simultaneously both for loading and unloading the ship as ramps 31e, 32b, and 32d clearly show. Ramps 31a and 32a are ramps of single width and they are used solely for ship-loading purposes. The trailers which are loaded upon the ship across ramps 31a and 32a are unloaded from the ship across ramps 31b and 32b, that is, to be more exact, across ramps corresponding to ramps 31b and 32b at the port of consignment of the ship's cargo. By the same token, trailers loaded upon the ship across ramps 31e and 32e are unloaded therefrom across ramps 31f and 32f or ramps corresponding thereto at the second mentioned port. It will, of course, be noted that ramps 31f and 32f are of single width only. This arrangement is shown somewhat more graphically in Fig. 1 since the doors at the ends of the ship are but single doors and the intermediate doors are double doors. Each single door provides either ingress or egress for a single trailer, whereas each double door provides ingress for one trailer and egress for a second trailer simultaneously.

Fig. 3 also shows how the trailers are arranged on the wharves to facilitate loading and unloading the ship. They are arranged in spaced groups, each group corresponding to a given trailer compartment on board ship. As one trailer from any one compartment on board ship is removed, another trailer from a given group of trailers is brought onto the ship and placed in the same compartment. The vacated place on the wharf is now filled by the trailer which was thus removed from the ship and its place on board ship is filled by shifting the remaining trailers in that particular compartment a distance equal to the width of one trailer in the direction of the vacated place in said compartment. Hence, the adjacent trailer takes the place of the removed trailer and by the same token a space is rendered vacant at the opposite end of the compartment for the newly loaded trailer. This process continues until all of the trailers of a given compartment are removed from the ship and all of the trailers of a given group of trailers on the wharf are loaded on board ship to take the places of the removed trailers. The same process causes the removed trailers to assume the locations on the wharf vacated by the newly loaded trailers. Since loading and unloading takes place simultaneously, the entire job may be completed in half the time that it would normally take by the conventional practice of first unloading the ship and then loading it.

Fig. 3 also shows facilities for tying up two additional ships at the wharves so that little time may be lost between the loading and unloading operations of the several ships. Fuel tanks 35 may be installed in the two wharves to refuel the waiting ships. Possibly they may also be used to replenish the fuel supply of the several tractors used on the two wharves, assuming that the same grade of fuel is employed both by the ships' engines and the tractor engines. If different grades of fuel are used, then separate tanks should be provided to serve the requirements both of the ships and of the tractors.

Referring now to the trailers and tractors

which are used in connection with the present invention, it will be seen in the drawing and understood that each trailer 40 is a conventional trailer without modifications of any kind for the purposes of the present invention. The trailer may be twenty-eight feet in length, or thirty-feet, or thirty-two feet in length, its exact dimensions being unimportant insofar as the present invention is concerned, although the apparatus herein described is intended principally for the larger trailers which are generally used for interstate hauling rather than for the smaller trailers which are used in intra-city operations.

Tractor 41 is, however, somewhat unconventional. It has no fifth wheel for engaging the kingpin of the trailer. Instead, it has a platform 42 with a pair of upwardly projecting pins 43 fixed thereon and a bumper 44 situated at forward end of said platform. The platform is mounted on hydraulic lift members 45 so that it may be raised to the position which it is shown to occupy in Fig. 7 or lowered to the position which it is shown to occupy in Fig. 6. Corners 46 at the back end of platform 42 are beveled off or tapered for a purpose which will shortly become apparent.

The fifth wheel which is necessary in the coupling of the tractor to the trailer is provided in the form of a portable fifth wheel assembly 50 which constitutes a completely separate and independent entity, permanently connected neither to the tractor nor to the trailer. It comprises a box-like member or saddle 51 having a fifth wheel 52 pivotally mounted thereon. Saddle 51 has a top, sides, and back, but it is open at the front or, stated differently, it has no front at all. A channel 54 is formed in its top portion, extending from front to rear, and open at the front and bottom. Corners 55 formed at the forward end of said channel are beveled or tapered complementarily to the bevel or taper of corners 46 of platform 42. The width of channel 54 slightly exceeds the width of platform 42 and its length slightly exceeds the length of said platform 42, exclusive of its bumper 44. When platform 42 is in its lowermost position, tractor 41 may be backed into the saddle 50, its platform 42 entering channel 54 of said saddle. The beveled corners 46 and 55 aforementioned facilitate entry of said platform 42 into said channel 54. The rearward movement of the tractor into the saddle ceases when bumper 44 engages said saddle. It will be noted that the top wall of the saddle is provided with holes 56 corresponding in dimensions and location to pins 43 of platform 42. These pins and these holes may also be complementarily tapered to facilitate entry of the pins into the holes. It will be understood that the pins will enter the holes when platform 42 is raised by its hydraulic mechanism to its upper position as shown in Fig. 7. The saddle and its fifth wheel are now securely locked on the back of the tractor and the tractor may proceed to engage the trailer in the usual manner. Compressed air hose 57 may be hooked onto the trailer in the usual manner to actuate its brakes.

The loading and unloading operations take place when the tractors are coupled to the trailers and they are backed onto the ship or pulled off the ship. See Fig. 8 and ramp 32d in Fig. 3. Referring now to Fig. 8, it will be seen that when a trailer is backed into a given compartment on board ship, its rear wheels ride up upon a ramp 60 until the rear part of the body and chassis of

the trailer is disposed above a conveyor belt 61. At the same time, fifth wheel assembly 59 occupies a position immediately above a second conveyor belt 62. Two operations are now formed to deposit the trailer upon said conveyor belts: In the first place, the ramp 60 is lowered until the chassis of the trailer rests upon conveyor 61, and in the second place platform 42 of the tractor is lowered until the saddle of the fifth wheel assembly rests upon conveyor 62. Further lowering of platform 42 will disengage its pins 43 from holes 56 of the saddle and the tractor will then be free to leave the trailer. Air hose 57 should, of course, be disconnected.

The unloading process is simply the reverse of the loading process. The tractor moves into position with respect to the fifth wheel assembly 59 and platform 42 is caused to rise to engage the saddle of said fifth wheel assembly and to elevate it above the level of conveyor 62. Ramp 60 is also raised until the body of the trailer is elevated above the level of conveyor 61 and the trailer is now free to move off the ship. When the tractor and its trailer reach an appointed location on the wharf, wheels 48a of the trailer are lowered and the forward end of the trailer is lifted out of engagement with the fifth wheel assembly. The tractor may then depart from the trailer and carry with it said fifth wheel assembly for use in engaging a second trailer and loading it on board ship in the manner above described.

There are two ramps 60 for each trailer compartment on board ship. One of the ramps is for the purpose of elevating the back of the trailer to the level of the rear conveyor support 61. The second ramp is for the purpose of removing the trailer from the rear conveyor support.

A description of ramp 60 and its operating mechanism follows. (See Figs. 14 and 15.) It will be noted that each ramp 60 is provided with a plurality of rollers 65 at its forward end and with a plurality of pivotally connected, internally threaded collars 66 at its back end. The rollers 65 rest upon a depressed plate 67 in the deck plating 68. The internally threaded collars 66 ride on a plurality of vertical screw shafts 69. When these screw shafts are turned in a given direction, collars 66 move upwardly thereon and carry with them the rear end of the ramp. The forward end of the ramp tends to roll backwardly on rollers 65 to the extent required. When the screw shafts are turned in the opposite direction, collars 66 are caused to move downwardly and the back end of the ramp is thereby lowered with said collars. The forward end of the ramp tends to move forwardly on said rollers 65.

The means whereby the screw shafts 69 are caused to rotate in either direction consists of a plurality of worm wheels 70 which are affixed to said screw shafts, a plurality of worms 71 which engage said worm wheels, a shaft 72 on which said worms are fixed, a bevel gear 73 affixed to said shaft 72, a second bevel gear 74 affixed to a shaft 75, and meshing with bevel gear 73, a gear box 76 to which shaft 75 is connected, and a crank handle 77 which is also connected to said gear box and which actuates the gears therein when it is worked in either direction. In other words, when the crank handle is operated in one direction, the ramp will be caused to move upwardly on screw shafts 69, and when the crank handle is operated in the opposite direction, said ramp will be caused to move downwardly on said shafts 69. Shaft 75 may be sup-

ported on bulkhead 26 by means of suitable bearings or brackets 78. Bearings 79, fastened to framework 80, may be used to support screw shafts 69 in vertical positions on deck plating 68.

It will be noted in Fig. 8 that framework 80 last above mentioned, extends longitudinally and centrally of the ship and between the trailer compartments on the two sides of the ship. A walk or runway 81 is provided on said framework so that the crew of the ship may walk from one end of each compartment to the other without having to crawl underneath the trailers. A bulkhead door 82 is provided in each bulkhead 26 to enable the crew to walk from compartment to compartment along the several catwalks 81. Bulkhead doors 82 are, of course, water-tight for emergency purposes.

It will be understood that each trailer compartment harbors a rear conveyor system 61 and a front conveyor system 62. The two rear conveyor systems 61 of each pair of transversely adjoining trailer compartments are supported on framework 80, one on each side of catwalk 81. (See Figs. 8, 12 and 13.) Framework 80 is elevated above the deck level and the upper run of each of these two conveyor systems is disposed above the framework and the lower run is disposed below it, but still above the deck level. More specifically, framework 80 consists of a plurality of uprights 80a supporting a plurality of horizontal beams or girders 80b. Mounted on the beams or girders is a pair of tracks 83 on which rollers 84 ride. These rollers are mounted on axles 85 which serve as connecting pins for conveyor sections 61a. A plurality of bearings 86 is provided on conveyor sections 61a and it will be noted that these bearings carry auxiliary rollers 89 which are disposed at a higher level than main rollers 84. As the conveyor belt moves longitudinally of itself, its upper reach or run is supported by rollers 86 and tracks 83. A pair of L-shaped bars 88 is provided below horizontal girder 80b, and it will be noted that these L-shaped bars serve as tracks for auxiliary rollers 89 on the lower run of the conveyor belt. (See Figs. 12 and 13.)

The front conveyor belt 62 is similar in construction to the rear conveyor belt 61 except that it comprises a pair of conveyor belts 62a and 62b, respectively, which are joined by means of cross bars 62c which are H-shaped in cross section. Hence, conveyor 62 requires two pair of tracks 83 instead of the single pair 85 which conveyor 61 requires. Bearings 86 carrying auxiliary rollers 89 are fastened to the H-beams 62c rather than to the conveyor sections 61a as is the case with conveyor system 61. Hence only two L-beams 88 are required to support the auxiliary rollers 89, even though conveyor 62 is really a double conveyor having two belts 62a and 62b, respectively supported by two pairs of tracks or rails 83. (See Figs. 10 and 11.)

Front conveyor system 62 is mounted to extend below the level of deck plating 68. (See Fig. 8.) It is supported by horizontal beams or girders 95, and it will also be noted that these horizontal beams or girders support the deck itself by means of H-beams 96. More specifically, girders 95 carry tracks or rails 83 as Figs. 8 and 10 clearly show. When a truck trailer is brought on board ship, its fifth wheel assembly 59 is deposited upon H-beams 62c. It will be noted in Fig. 10 that the top surface of these beams is disposed at a slightly higher level than the top surface of

the deck. The reason for this will become apparent from an examination of Fig. 8. It will there be seen that one of the truck trailers is supported by means of a fifth wheel assembly or saddle 50 which projects over the side of conveyor 62. Were this conveyor not raised above the level of the deck, said fifth wheel assembly, and more particularly its saddle member, would rest in part upon the conveyor and in part upon the deck, and hence it would be impossible to move the trailer from one location to another through the instrumentality of the two conveyor systems.

Fig. 16 shows in diagrammatic view how the conveyor systems are operated. A gear reduction motor 109 is connected by means of drive shaft 101 and sprocket wheels 102 to the front conveyor belt 62, and a similar gear reduction motor 104 is connected by means of drive shaft 105, sprocket 106, idler 107, and sprockets 108 to the rear conveyor belt 61. These two motor drives should be synchronized to cause the two belt systems to operate simultaneously and in unison.

Fig. 17 is a view of another wharf arrangement which may be employed in place of the arrangement shown in Fig. 3. Here one of the wharves is provided with a lower level 110 and with an upper level 111, and the other wharf is provided with a lower level 112 and an upper level 113. A ramp 114 provides access to upper level 111 and a similar ramp 115 provides access to the other upper level 113. Hence all of the trailers which are to be loaded upon the lower deck of the ship may be deployed upon lower levels 110 and 112, and all of the trailers which are to be loaded upon the upper deck of the ship may be deployed upon the upper levels 111 and 113, respectively.

It will be understood from the foregoing that what has hereinabove been described is a preferred form of the present invention, but slightly modified in Fig. 17, and that this preferred form may be modified in many ways within the broad scope and spirit of the invention.

Having thus described my invention, what I claim as new and desire to secure by Letters Patent, is:

1. Apparatus for loading truck trailers upon a ship, moving the truck trailers from a loading to an unloading position on board ship, and unloading said truck trailers from the ship, said apparatus including a pair of conveyors on board

ship, one for supporting the front end, and the other for supporting the back ends of the trailers and for moving them from one position to another, the conveyor for the backs of the trailers being disposed at an elevated level relative to the front conveyor, a ramp adjacent the rear conveyor to facilitate raising the back ends of the trailers to the level of the rear conveyor, said ramp being lowerable to deposit the back ends of the trailers upon said rear conveyor, and to remove all load from the trailer springs and wheels, said ramp being raisable under said wheels to elevate the back ends of the trailers above the level of the rear conveyor for removal therefrom and to re-transfer the load from said conveyor to said wheels and springs, a portable supporting member between the surface of the front conveyor and the front end of each trailer to support said front end of the trailer on said front conveyor, said portable supporting member being provided with a fifth wheel which engages the kingpin of the trailer.

2. Apparatus in accordance with claim 1, wherein a tractor is provided for engagement with the portable supporting member, said tractor being provided with raising and lowering means for raising the portable supporting member above the level of the front conveyor preparatory for deposit thereon and removal therefrom of said portable supporting member, and for lowering the supporting member upon said front conveyor.

HENRY D. CLEVELAND.
